(57) **CLAIM**

The ornamental design for a vehicle light assembly, as shown and described.

DESCRIPTION

FIG. 1 is a perspective view of a vehicle light assembly, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an operational front elevation view thereof in an environment of use.

The broken lines in the drawings illustrate portions of the article that form no part of the claimed design. All unshaded surfaces adjacent to broken lines form no part of the claimed design. The additional broken lines in FIG. 9 show environmental subject matter forming no part of the claimed design.
